UNITED STATES PATENT OFFICE

2,325,171

ROLL MILL COVER AND VEHICLE CONTROL

Isidor M. Bernstein, Cincinnati, Ohio, assignor to
Interchemical Corporation, New York, N. Y., a
corporation of Ohio

Application August 3, 1940, Serial No. 350,341

2 Claims. (Cl. 83—22)

This invention relates to multi-roll mills which are ordinarily used for grinding paints, enamels, inks and the like, and the invention is particularly directed to a means for preventing excessive evaporation of the volatile constituents of the vehicle from the mixture being ground and the maintenance of substantially constant and uniform composition in the mixture by providing continuous replacement of the small amount of solvent unavoidably lost during the grinding operation.

Ordinarily, dispersed pigments, inks, and the like are subjected to an extremely fine grinding and dispersion by passage of the mixture through a roll mill having at least three rollers, in which the pigment is fed between the first two rollers and then passes between the second and third roller for a second grinding before being removed as a paste from the third roller by means of a doctor knife. Where the pigment is difficultly dispersible the mill may employ more than three rollers in series so that the paste passes consecutively between a large number of rollers before finally being removed from the mill.

A serious difficulty which has been encountered in the milling of pigment in volatile vehicles, and especially in the case of the water emulsion inks and aniline inks in which the vehicle is a solution of a spirit-soluble resin in alcohol, has been the loss of volatile solvent during grinding. The result of this has been that not only a non-uniform product is produced, but often the pigment becomes precipitated or agglomerated in spots and the resulting product is commercially undesirable. The most common device employed heretofore to prevent excessive solvent evaporation during such grinding operations has consisted in a hood or covering which could be placed over the grinding rolls to reduce air circulation. However, unless sealed joints or packing glands are used on the hood where it surrounds the roller axles, some solvent is unavoidable lost at these places. From the practical standpoint, a completely sealed hood is not always desirable, as this involves complicated and time-consuming labor when it is desired to clean the rollers prior to the grinding of a different pigment.

It is therefore an object of this invention to provide a simple and easily detachable apparatus for multi-roller mills which will reduce excessive loss of solvent by evaporation and will maintain a substantially constant and uniform composition of the mixture being milled. Another ob-

ject is to provide a device which will, when used in connection with a multi-roller mill, permit the successful and efficient grinding and dispersion of aniline inks, especially water emulsion of aniline inks, as well as similar dispersions in volatile solvents. Other objects will be apparent from the following description.

In the drawing, Fig. 1 is a cross sectional view of the side of a three roll mill employing a cover and solvent replenisher which is a typical embodiment of the present invention; and

Fig. 2 is a view of the mill, taken along the line 2—2 of Fig. 1.

Referring to Figs. 1 and 2, grinding rollers A, B and C are supported by a frame D which also supports the rack E by means of which the position of end plates F may be adjusted with respect to the surfaces of the rolls A and B, all of which is standard roll mill construction.

The device of the present invention, as applied to a three roll mill, comprises a section G which fits over the frame D and the end plates F, and a section H which correspondingly covers the rollers B and C.

The section G, which is placed over the feeding end of the mill, comprises fixed covers 10 and 11 fastened to the mill frame D and a movable cover 12 fastened to the fixed cover 10 by means of hinges 13. In operation, the material to be ground is placed on the feed roller A which carries the material between itself and the second roller B. By means of the hinged cover 12, the roller A is easily accessible. The main purpose of the section G of the invention is to keep dirt out of the material being ground and to lessen the rate of solvent evaporation by preventing large air currents from coming in contact with the material being ground or dispersed.

Between the sections G and H is a baffle plate 14 mounted over the roller B for the purpose of substantially isolating the space enclosed by the section H from the section G, inasmuch as the concentration of solvent vapor in the section H is greater than elsewhere and should be held as nearly constant as possible in order to obtain a perfectly uniform, and controlled, solids content in the finished dispersion. Also, the baffle 14 decreases the solvent loss due to evaporation.

The section H comprises an enclosure 15 to which a movable cover 16 is attached by hinges 17, and a tank 18 which is provided with tubes 19 and valves 20. The movable cover 16 protects the product from the mill from contamination with dirt and other foreign particles which

might otherwise drop in the product as it is being removed from the roller C by means of a doctor blade 21, and passed into any desired receptacle by means of a trough 22. Solvent, or vehicle, to be added to the material being milled, to make up for losses, is placed in the tank 18 and supplied to the rollers B and C through the tubes 19. The rate of addition of solvent to the material being milled is controlled by the valves 20 and is adjusted in each milling operation to balance the loss of solvent by evaporation. The pipes 19 are placed so as to deliver the solvent, by dripping, on the last two rollers in the mill (rollers B and C) near the edges of the rollers where the maximum evaporation of the solvent occurs. By this method the concentration of solvent in the mixture being milled and discharged may be maintained uniform. At the same time the loss of solvent by evaporation is reduced to a practical minimum by supplying the make-up solvent only to the last two rollers of the mill and isolating the air space immediately above these rollers from the rest of the mill.

A mill employing more than three rollers may be provided with a cover and make-up solvent supply and distributing system, such as is illustrated by the section H in the drawing, and this section may be modified and extended to cover more rollers than just the last two, with provision for supplying solvent to each roller. The essential features are that the upper surfaces of at least the last two rollers must be at least partially enclosed and that the make-up solvent should be supplied in continuous small amounts, preferably near the ends of the rollers. The factor which determines the number of rollers to be supplied with make-up solvent is primarily the thinness of the film of milled material which spreads on the rollers, as the solvent evaporation from thin films is much greater than the evaporation ordinarily occurring on the feed roller where a relatively large quantity of unground material is present. Other variations will be apparent to those skilled in the art, and the in-

vention should not be limited other than as defined by the appended claims.

I claim:

1. Apparatus for controlling the solvent or vehicle concentration in a pigment dispersion during milling on a three-roller mill, which comprises, in combination, the three rollers of said mill positioned adjacent one another and with parallel axes, a covering substantially enclosing the upper surfaces of said rollers to reduce solvent evaporation from said dispersion, a baffle placed substantially over the center roller so that the space within said covering and above the third roller is substantially isolated from the space above the first roller, a liquid reservoir, conduits connected with said reservoir, valves in said conduits to control individually the flow of liquid to said rollers, said conduits positioned so that on opening said valves liquid is caused to flow by gravity onto said rollers near the ends thereof whereby the solvent concentration in said dispersion is maintained uniform and constant throughout the grinding operation.

2. Apparatus for controlling the solvent or vehicle concentration in a pigment dispersion during milling on a three-roller mill, which comprises, in combination, the three rollers of said mill positioned adjacent one another and with parallel axes, said axes lying substantially in a horizontal plane, a covering substantially enclosing the upper surfaces of said rollers to reduce solvent evaporation from said dispersion, a baffle placed substantially over the center roller so that the space within said covering and above the third roller is substantially isolated from the space above the first roller, a liquid reservoir mounted on said covering, conduits connected with said reservoir, valves in said conduits to control individually the flow of liquid to said rollers, said conduits positioned so that on opening said valves liquid is caused to flow by gravity onto said rollers near the ends thereof whereby the solvent concentration in said dispersion is maintained uniform and constant throughout the grinding operation.
